UNITED STATES PATENT OFFICE.

JAMES J. WOOD, OF BROOKLYN, NEW YORK.

HANGER-BOARD FOR ARC LAMPS.

SPECIFICATION forming part of Letters Patent No. 398,870, dated March 5, 1889.

Application filed December 14, 1887. Serial No. 257,867. (No model.)

To all whom it may concern:

Be it known that I, JAMES J. WOOD, of Brooklyn, Kings county, New York, have invented certain new and useful Improvements 5 in Hanger-Boards for Electric Lamps, of which the following is a specification.

My invention relates to that class of suspending boards or supports from which electric-arc lamps are hung and to which the 10 line-wires connect. These boards are usually provided with binding-posts, to which the line-wire connects, and with polar suspension hooks or loops, to which the poles of the lamps connect and from which the lamp hangs, with 15 a compound switch arranged to make one connection between the binding-posts and the polar hooks and another connection directly between the posts themselves.

In the drawings annexed, Figure 1 presents 20 a perspective view of my improved hanger-board adapted for street or outdoor lamps. Fig. 2 is a small perspective view of a lamp hung from the hanger-board, showing the manner of engagement with the improved 25 polar suspension-loops, the other features of the board being omitted. Fig. 3 is a cross-section on x x of Fig. 1. Fig. 4 is a plan view of a somewhat modified form of hanger-board adapted for indoor uses, and Fig. 5 is a 30 cross-section thereof, and Fig. 6 a detail. Fig. 7 is a sectional plan of another form of hanger-board for indoor use, in which a similar form of switch is used, but the polar suspension hooks or loops are omitted. Fig. 8 is a cross- 35 section of Fig. 7 on o o , and Fig. 9 is a cross-section on y y .

I will first describe the leading form of my invention. (Shown in Figs. 1, 2, and 3.) In these views, a indicates a base-board, preferably of well-seasoned wood and of oblong form, with corners cut off, and adapted to fit 40 into the top of the hood or reflector used in street-lamps, the under side of which is fitted with the operative features of the hanger-board, as shown. At the center of this board is a hatch or opening, b , to permit the upward protrusion of the tubes which inclose the carbon-holders of the lamp, as seen in Fig. 2, and from the base-board on each side of this opening 45 depend the polar suspension eyes, hooks, or loops c c , which form the terminals of the line on the board and connect with the poles

of the lamp, or from which the lamp is hung, as seen in Figs. 2 and 3. It will be seen that the lamp connects with the polar loops by 55 means of metal hooks d , fixed on the poles or binding-posts of the lamp, which thus hook into and hang from the polar loops, as will be readily understood from Figs. 2 and 3, and thus connect the lamp with the line, as is now 60 usual in suspending electric lamps.

On referring to Figs. 1 and 2, it may be observed that the loops c project from a metallic base-plate, e , which is screwed to the base-board a , and that a spring-tongue, f , secured 65 at one end to the base-plate e , projects at the free end into each loop and presses toward or against the bight of the loop, as well shown in Fig. 1 and in dotted lines in Fig. 5, which spring forms one of the novel and 70 advantageous features of my improvement. It will therefore be seen on reference to Figs. 1 and 2 that when the polar hooks d on the lamp are hooked into the loops the springs f will be raised and will press firmly on the hooks, 75 holding them firmly in the loops.

It will be noted from Figs. 1 and 2 that the springs f are directed in opposite directions, and that the hooks d on the lamp are also turned in opposite directions, so that the 80 lamp is therefore readily engaged with the loops and springs by first pressing the hooks on the lamp up against the springs until the springs are lifted, and then, by a partial rotation of the lamp, causing the hooks to slip 85 into the loops under the springs, as seen in Fig. 2, and also partially in Fig. 5, thus hooking the lamp quickly and securely to the hanger-board. It may now be readily comprehended that the springs f not only tend to hold the 90 hooks down in firm engagement with the loops, and thus render the electrical contact positive and certain, but they also prevent the hooks from becoming raised or separated from the loops, and thus detached mechanically by the swaying, shaking, or other movements of the lamp. The most important function of the springs, however, is to prevent any electrical separation of the loops and hooks caused by movement or jar such 95 as would cause an arc to form, and thus burn or destroy the connections or set fire to the board—a thing which is likely to occur with the ordinary open loops, in which the hooks

on the lamp are liable to become separated unless actually locked down by wedges, as is often done to prevent such separations, but which trouble is obviated by my improvement.

Now in hangers for arc lamps the polar loops are not of course connected directly to the line, but a switch is interposed between the loops and the line arranged to put the loops into and out of circuit, as occasion requires.

The switch which I employ is of somewhat novel construction, and is shown in different forms in Figs. 1 and 4.

Referring to Fig. 1, g g' are the binding-posts on the base-board, in which the ends of the line-wires are received, as indicated by full lines, and on each binding-post is pivoted a metallic switch-bar, h h' , which two bars project therefrom in parallel lines like two parallel links, and are mechanically connected at or about the middle by a transverse non-conducting cross-bar or link, i , as fully shown in Fig. 1. In the path of the outer end of these switch-bars h h' are arranged three contact seats or clasps, k k' k^2 , the seat k being attached directly to the base-plate of one of the polar loops, and hence in electrical connection with that loop, while the seat-clasp k' is connected by a wire, j , with the base-plate of the other loop. The third seat-clasp, k^2 , is connected by a wire, l , with the line binding-post g' .

Now m indicates an operating-lever, preferably made of a thin stiff bar of flat steel or iron, which projects loosely through a slot in the insulating-link i , and is pivoted thereto by the pivot-pin m' , while the short arm of the lever projects through an opening in the base-board and engages a slot in an abutting-plate, n , fixed to the base-board over said hole, while the long arm of the lever projects freely downward for manipulation, as seen in Figs. 1 and 3. Now on either side of the base-board, at opposite sides of the switch, are marked the words "On" and "Off," to indicate the direction in which to shift the switch to turn the current on or off or put the lamp in or out of circuit, as usual. It will therefore be seen that when the switch is shifted to the "off" side, as shown by full lines in Fig. 1, the loops c c will be cut off from the line, and the line closed between the binding-posts g g' , and the current will now flow from the line to the post g , and thence by wire l to the seat-clasp k^2 , to the switch-bar h' , and thence to post g' to the other branch of the line, thus leaving the line uninterrupted at the hanger-board, while the lamp or its hangers c c are disconnected, or absolutely cut off from the line. If, however, the switch is shifted to the "on" side, as indicated by dotted lines, the current will now flow from the post g by switch-bar h , seat k' , and wire j to the loop c on the left, thence through the lamp to the loop on the right, and thence by the seat k and switch-bar h' to the

post g' , and thence to the line, thus putting the lamp in circuit.

When it is desired to cut the lamp off the line, the switch will of course be shifted back into the first-described position, shown in full lines, and it will be noted on reference to Fig. 1 that in thus cutting the lamp out of circuit the switch will always close the connection between the posts g g' before it breaks it with the hanger-loops c c , so as to always keep the line intact whether the lamp is on or off. Thus on reference to Fig. 1 it will be seen that the seat-clasps k and k^2 are placed at such a distance from each other with reference to the width and movement of the switch-bar h' that the said bar will always enter the clasp k^2 before it leaves the clasp k , and thus always close the circuit between the line-posts before breaking it between the lamp-loops.

The hanger-board shown in Figs. 4 and 5 is of somewhat simpler construction, but not so strong as in Fig. 1, being adapted for lighter use or for indoor lamps. The same elements exist in substantially the same arrangement; but it will be noted that one of the switch-bars, h' , is prolonged to act as the operating-lever, and is provided with a non-conducting knob, h^2 , for manipulation. The connecting-link, between the switch-bars is partly a non-conducting bar, i , and partly a conducting-bar, o , having a prong adapted to engage with the seat or clasp k^2 , connected with the binding-post g' . The seat k connects to one of the loops c and the seat k' to the other loop, the same as before described. These seats are simply U-shaped clasps of spring-brass, as seen in Fig. 6. It will therefore be seen that when the switch is slipped to the right, as in Fig. 4, the line will be closed between the posts and the lamp cut off, the current flowing from the post g by switch-bar h , connecting-bar o , and seat k^2 to the post g' , while the connection is broken between the seats k k' and switch-bars h h' . To put the lamp into circuit, however, the switch is shifted in the opposite direction, when the bars h h' will contact with the clasps k k' , and the bar o will break contact with the seat k^2 just after the contact is made with the seats k k' , thus closing the line through the lamp and breaking it between the posts, with the same effect as already described in reference to Fig. 1.

In Figs. 4 and 5 it may be noted that the loops c and the base-plates e are formed integral out of one piece of sheet metal, whereas in Fig. 1 the loops and base-plate are cast in one piece; but the loops may be made separate and riveted or secured in the base-plate, if desired, either construction being used, as preferred.

In Figs. 7, 8, and 9 is shown another form of hanger-board for indoor use. In this case the base-board is formed of an upper and lower layer, a and a' , of circular form, secured together with a space between in which is ar-

- ranged the switch mechanism, the hanger-loops, with their springs, &c., being entirely omitted. In this case the lamp is suspended centrally from a central hook, *p*, depending from the middle of the under board, and the binding-posts of the lamp are connected by wires *r r'*, which pass through holes in the lower board, *a'*, and connect one to the binding-post *g* and the other to the seats *k* and *k'*.
- 10 The seats *k* and *k'* are connected together, and one of the line-wires connect to the seats *k k'* and the other runs to the binding-post *g'*, as best shown in Fig. 7. The two switch-bars *h h'* are connected by a non-conducting link or cross-bar, *i*, which extends centrally or diametrically of the circular board, and is prolonged beyond the switch-bars and protrudes for manipulation at each end from between the inner and outer layers of the board,
- 15 as shown best in Fig. 9. Cords or wires *s*, as shown by dotted lines in Fig. 9, may be attached to each end of the bar *i* and be run to any desired point from which it is desired to operate the switch; or a cord, *t*, may be secured at the middle to the bar *i* and run over pulleys *t'* at each end, and be secured to pendent pulls or tassels *u*, by which the switch may be shifted in either direction, as will be readily understood from Figs. 7 and 9.
- 20 The words "On" and "Off" are inscribed on each end of the operating-bar *i*, so that either will show over the edge of the under board, *a'*, when the bar is shifted in the appropriate direction, thus indicating the condition of the
- 25 switch and guiding the operator in manipulating the same. It will therefore be seen

that when the switch is shifted in the "On" position, as shown by full lines in Fig. 7, the lamp will be put in circuit and the current will flow from the line-wire to post *g'*, and by 40 bar *h'* and seat *k* by wire *r'* to the lamp, and from lamp by wire *r* to post *g*, and thence by bar *h* and seat *k'* to the other line-wire, thus completing the circuit through the lamp. On 45 the other hand, when the switch is put in the "Off" position, as shown by dotted lines in Fig. 7, the connection between the line-wires will be closed before the connection with the lamp is broken, and the current will then flow from the post *g'* directly by the bar *h'* and 50 seats *k k'* to the opposite line-wire, as will be readily understood on reference to Fig. 7.

What I claim is—

1. In a hanger-board for electric lamps, the combination, with conducting suspension 55 eyes or loops in connection with the terminals of the circuit, of conducting-springs, also in connection with the terminals of the circuit, adapted to press into the loops, with polar hooks or suspenders on the lamp adapted to 60 engage between the loops and the springs, substantially as shown and described.
2. In a hanger-board, a suspension device formed of a base-plate, *e*, loop *c*, and spring *f*, both the loop and spring being in metallic 65 contact with the base-plate, substantially as and for the purpose set forth.
